CONVERSION OF HYDROCARBON OIL

Original Filed April 23, 1932

UNITED STATES PATENT OFFICE

2,055,015

CONVERSION OF HYDROCARBON OIL

Jacque C. Morrell, Chicago, Ill., assignor to
 Universal Oil Products Company, Chicago, Ill.,
 a corporation of Delaware

Application April 23, 1932, Serial No. 607,020
 Renewed May 15, 1935

4 Claims. (Cl. 196—48)

This invention relates more particularly to the pyrolytic conversion of the heavier and less valuable portions of crude petroleum such as the heavy distillates and residua produced therefrom in the primary distilling steps though the process is also applicable to heavy hydrocarbon oil mixtures produced from other sources.

In a more specific sense the invention comprises a process which permits the simultaneous 10 production of high yields of motor fuel fractions of improved anti-knock value along with the production of coke of low volatile content.

In the cracking processes at present used in oil refineries numerous difficulties are 15 encountered when attempts are made to increase the yield of motor fuel from any given stock beyond a certain point. With the application of cracking conditions of increasing severity higher anti-knock motor fuel is produced, but the yield 20 diminishes on account of excessive gas formation, and carbon troubles, particularly in the tubes of heating elements, limit the safe operating periods between cleanouts on account of the development of "hot spots" and the possibility of serious fires due to tube ruptures.

The production of coke of low volatile content requires relatively high temperatures and low pressures, and if such conditions obtain in tubular heating elements there is an increased tendency 25 toward deposition of hard carbon with resultant local overheating while if they obtain in both the tubes and the reaction zone high gas losses occur with a corresponding decrease in the overall yield in gasoline. The present process 30 comprises an improvement in operating steps allowing the production of low volatile coke along with a high yield of good anti-knock value gasoline as will be hereinafter fully described.

In one specific embodiment the invention comprises cracking hydrocarbon oils at elevated 35 temperatures and pressures during passage through a heating element and an enlarged reaction chamber, passing the cracked products to a reduced pressure coking chamber wherein further conversion is effected by the introduction of flue gases and reheated gaseous and liquid products from the process, separating coke from vaporous and gaseous products, fractionating the vapors and gases to produce a mixture of fixed 40 gases and vapors of gasoline boiling range, intermediate refluxes and heavier refluxes suitable for further conversion, condensing said gasoline vapors and separating the fixed gases therefrom, separately heating said fixed gases and/or gasoline vapors and returning them to the coking

chamber, separately heating said intermediate refluxes and returning them to the coking chamber and returning said heavier refluxes to the primary cracking zone for further conversion.

The nature of the process may be conveniently described in connection with the attached drawing, which shows diagrammatically in side elevation by the use of conventional figures a plant layout in which characteristic operations may be conducted.

Referring to the drawing, raw charging oil may be introduced to the plant from line 1, containing control valve 2, and discharged through pump 3 and line 4, containing a control valve 5, to mingle with heavy refluxes from the line 9, these 15 refluxes coming from the plant fractionator 22 by way of line 6, valve 7, pump 8, line 9 and valve 10'. A portion of the raw charging oil may be introduced into the fractionator if desired, though means for this are not shown in the 20 drawing.

The combined feed of raw oil and fractionator 25 refluxes passes through a heating element 10 disposed to receive heat from a furnace 11 and during its passage through the element receives heat sufficient to initiate a limited amount of cracking, a pressure being maintained at the same time by the use of succeeding valves in the lines following the reaction chamber. The severity 30 of cracking conditions imposed upon the combined feed oils during their passage through the heating zone is preferably held within the range of operating conditions corresponding to a minimum of coke formation in the tubes, the temperature range corresponding to such conditions 35 being approximately 850 to 950° F. and the pressure from 100 to 400 pounds per square inch, depending upon the character of the combined feed undergoing treatment and other circumstances.

The heated products from element 10 pass to 40 enlarged chamber 14 either by way of line 12, containing control valve 13, or line 12', containing control valve 13', receiving reheated side cuts from the fractionator from line 44 as will be later described. Two alternate flows may be employed in 45 reaction chamber 14, depending upon the character of the stocks treated. In one case corresponding to oils of relatively low carbon-forming tendencies the heated products may be passed downwardly through the reaction chamber and 50 all products, both vaporous and non-vaporous, may pass through line 15 and control valve 16 to the low pressure coking chamber 17.

The other alternative flow which may be used 55 in the case of oils of relatively high coke-forming

tendencies consists in adding the products from the heating element to the lower portion of the reaction chamber through a line 12', containing control valve 13'. In this method of operation 5 the heavier residual liquids are quickly separated from the vapors in the bottom of the reaction chamber so that they receive less cracking time than the vapors which must traverse the entire length of the chamber before being released 10 through line 15' and control valve 16'. Thus, the vapors are more extensively cracked in the reaction chamber than the non-vaporous products, and coke formation is minimized.

The pressure employed in coking chamber 17 15 is preferably lower than that employed in the previous cracking zone and the temperatures are preferably higher. To insure these conditions which are necessary for production of a high grade low volatile coke, combustion gases may be introduced through a line 66, containing a control valve 67, from any source such as, for example, the various furnaces of the process, suitable blowers or pumps having been used to step up the pressure to the necessary point. In addition, reheated 20 side cuts and/or intermediate hydrocarbon fractions from sources outside the process may be introduced into the coking chamber from line 46 and reheated end product gases and liquids from the process may be introduced from line 64, containing control valve 65, the previous heat treatment 25 of these heat-carrying media being described in order in following paragraphs. The coking chamber is shown having a line 18, containing control valve 19, to permit the withdrawal 30 of any liquid accumulations at any period in the operations of the plant in which they may accumulate.

It will be seen from a recounting of the various provisions made for furnishing additional heat 40 to the low pressure coking chamber through the media of flue gases and highly heated products of the process that conditions may be modified to take care of any particular situation, by controlling the relative proportions of flue gas and other 45 heated materials added. Thus, flue gases at temperatures of from 1100 to 1700° F., or thereabouts, may be admitted unless it is found that relatively high temperatures are necessary to produce coke of low volatile content and coking may also be induced by the use of process liquids superheated 50 to temperatures in excess of 1,000° F., these products being concurrently cracked to increase their anti-knock value.

The vaporous products from the coking chamber 55 may pass through a line 20, containing control valve 21, and enter a fractionator 22 which is preferably of a design and capacity sufficient for separating vapors of gasoline boiling range as an overhead fraction, leaving insufficiently converted 60 refluxes to be returned to the cracking and/or coking zones of the process. The overhead fractions may pass through line 23, containing control valve 24, and through condenser 25 in which the cooled fixed gases and gasoline boiling range liquids 65 may be conducted to a receiver 28 by way of a line 26 and a control valve 27, this receiver having a gas release line 29, containing control valve 30, and a liquid draw line 31 containing control valve 32.

70 Side cuts which may be advantageously employed as heat carriers for the coking step may be withdrawn through such lines as line 33, containing control valve 34, and line 35, containing control valve 36, these lines leading to a pump 37. 75 If desired, outside stocks of the general character

of such side cuts may be introduced to line 33 from a line 1', containing a valve 2'. Pump 37 discharges through line 38 and control valve 39 into and through a heating element 40 disposed to receive heat from a furnace 41 and the side cuts are 5 preferably heated to produce a controlled degree of cracking and bring them to a temperature suitable for best operating conditions in the succeeding reaction and/or coking chamber to which they may be subsequently introduced. The generally 10 light character of these side cuts will normally require relatively high temperatures and pressures for their decomposition, characteristic temperatures being included between 950 and 1100° F., more or less, and pressures of several hundred 15 pounds per square inch, for example, 500 to 600 pounds.

The heated and cracked side cut fractions may pass through a line 42, containing control valve 43, and having branch line 44, containing control valve 45, and leading to line 12' and branch line 46, containing control valve 47, and leading to coking chamber 17. The relative amounts diverted to the transfer line from the primary heating element and to the coking chamber will be 25 adjusted to produce optimum treating effects.

The invention further contemplates the use of both the gases and the overhead distillates from the process as heat-carrying media when benefits are obtained by their use or when in the case of 30 the liquid condensates they are improved in anti-knock quality by further heat treatment. Thus, a portion of the fixed gases from the process may be diverted to a pump 50 through a branch line 48, containing a control valve 49, and discharged therefrom through a line 51, containing a control valve 52, and leading to line 38 or a portion thereof may be diverted from line 51 to line 60 to be presently described through line 53, containing control valve 54. 40

A portion of the end point distillates may be separately heated in heating element 62 disposed to receive heat from a furnace 63, passing through line 57, containing control valve 58, to pump 59 which discharges through line 60, containing control valve 61. Line 60 is shown in operating conjunction with line 38 through branch line 55, containing control valve 56.

From the description of the various recirculating lines just given it will be evident that any of 50 the products of the process may be heated singly or in combination with other products in either of the auxiliary heating elements 40 and 62 so that the process is seen to possess complete flexibility in the matter of re-forming the primary 55 products or utilizing them as heat carrying media for the coking operation.

As an example of the improved results obtainable in the production of high yields of good anti-knock gasoline along with the production of low 60 volatile coke, an example may be cited involving the cracking of a Mid-Continent topped crude, first by ordinary cracking processes in which conditions are chosen to permit coking under pressure in the reaction chamber and, second, by operations characteristic of the process of the present invention involving the use of a low pressure, high temperature coking chamber following the high pressure reaction chamber, re-formation of side cuts from the fractionator and their introduction into the coking chamber and the use of hot flue gases in the coking chamber. 65

In the high pressure coking operation in a plant of the ordinary coil and chamber type the temperature maintained at the exit of the heating 75

element may be 930 to 935° F. and the pressure approximately 250 pounds per square inch. In the improved process of the present invention using a setup generally similar to that shown in 5 the drawing, the temperature and pressure may be approximately the same with introduction of the heated products from the primary heating element into the bottom of the reaction chamber and the separation at that point of the heavier 10 coke-forming products as described in connection with the drawing. The pressure in the coking chamber may be approximately 30 to 50 pounds per square inch and the temperature from 1100 to 1200° F. Approximately 40% of the flue gas 15 product from the primary cracking furnace may be introduced from the coking chamber and a side cut representing that portion of the gasoline product boiling between 325 to 400° F. may be re-formed in the secondary heating element at 20 a temperature of 1000° F. and a pressure of 500 pounds per square inch and introduced into the coking chamber.

The yields and quality of products which may be obtained from the older and more generally 25 used type of operation are indicated in Table I, while those which may be produced by the use of the present process are given in Table II.

Table I

30	Gasoline, 54.5 gr., 400 E. P.	
75	O. N.*	58% by volume
Gas oil, 29.0 gr.		5% by volume
Coke, 14% volatile content	100# per bbl. raw oil	
Fixed gas	600 cu. ft./bbl. raw oil	

Table II

35	Gasoline, 53.5 gr., 405 E. P.	
82	O. N.*	60% by volume
Gas oil, 28.0 gr.		6% by volume
Coke, 4% volatile content	88# per bbl. raw oil	
Fixed gas	590 cu. ft./bbl. raw oil	

*Octane number.

The foregoing specification and example are 45 indicative of the invention and its improvements over similar processes, but neither are to be construed as imposing limitations upon its scope as they are given solely for illustrative purposes.

I claim as my invention:

50 1. In a process wherein hydrocarbon oil is subjected to cracking conditions of temperature and superatmospheric pressure in a heating coil and communicating reaction chamber, the vapors and non-vaporized residue from which are discharged into a coking drum, the vapors leaving the coking drum being subjected to fractionation to produce an overhead product, which is recovered, and an intermediate reflux condensate and a heavy reflux condensate which is returned, together with the charging stock, to the heating coil for further conversion, the improvement which comprises subjecting the intermediate reflux condensate 55 containing said heavy gasoline ends to cracking conditions in an independent heating coil and introducing the same into the coking drum whereby to devolatilize and coke the non-vaporized contents therein, and introducing hot flue gases 60 into the coking drum to further assist in devolatilizing and coking the non-vaporized residue 65 therein.

the same into the coking chamber to devolatilize and coke the non-vaporized contents therein.

2. A conversion process which comprises heating hydrocarbon oil to cracking temperature under pressure in a primary heating zone, discharging the heated oil into an enlarged reaction zone maintained under cracking conditions of temperature and pressure, removing vapors and unvaporized oil from the reaction zone and distilling the latter in a separating zone maintained 10 under lower pressure than the reaction zone, fractionating the vapors and separating therefrom relatively heavy and light reflux condensates and a fraction containing hydrocarbons boiling within the gasoline range, returning such 15 heavy reflux condensate to said primary heating zone, heating the light reflux condensate in a secondary heating zone to higher cracking temperature than the oil in said primary zone and then introducing at least a portion thereof 20 to the reaction zone, heating a portion of said fraction in a third heating zone sufficiently to enhance the anti-knock value thereof and introducing the same to the separating zone to assist the distillation of the unvaporized oil therein. 25

3. A conversion process which comprises heating hydrocarbon oil to cracking temperature under pressure in a primary heating zone, discharging the heated oil into an enlarged reaction zone maintained under cracking conditions of temperature and pressure, removing vapors and unvaporized oil from the reaction zone and distilling the latter in a separating zone maintained 30 under lower pressure than the reaction zone, fractionating the vapors and separating 35 therefrom reflux condensate heavier than gasoline and a lighter fraction containing hydrocarbons boiling within the gasoline range, heating such reflux condensate in a secondary heating zone to higher cracking temperature than the oil 40 in said primary zone and then introducing at least a portion thereof to the reaction zone, heating a portion of said fraction in a third heating zone sufficiently to enhance the anti-knock value 45 thereof and introducing the same to the separating zone to assist the distillation of the unvaporized oil therein.

4. In a process wherein hydrocarbon oil is subjected to cracking conditions of temperature and pressure in a heating coil and communicating 50 reaction chamber, the vapors and non-vaporized residue discharged into a coking drum, the vapors leaving the coking drum being subjected to fractionation to produce an overhead product, which is recovered, an intermediate reflux condensate 55 containing heavy gasoline ends and a heavy reflux condensate which is returned, together with charging stock, to the heating coil for further conversion, the improvement which comprises subjecting the intermediate reflux condensate 60 containing said heavy gasoline ends to cracking conditions in an independent heating coil and introducing the same into the coking drum whereby to devolatilize and coke the non-vaporized 65 contents therein, and introducing hot flue gases into the coking drum to further assist in devolatilizing and coking the non-vaporized residue therein.

JACQUE C. MORRELL.
